[57] CLAIM

The ornamental design for a table, as shown and described.

DESCRIPTION

FIG. 1 is a perspective front view of the table of my design;
FIG. 2 is a top view of the table;

FIG. 3 is a front view of the table (the rear view is a mirror image of the front view and is not shown); and, FIG. 4 is a left side view of the table (the right side view is a mirror image of the left side and is not shown).

The bottom of the table is flat and unornamented.
